Inventor:

W. A. Sloan

UNITED STATES PATENT OFFICE.

WILLIAM A. SLOAN, OF CINCINNATI, OHIO.

HAIR-FASTENER.

SPECIFICATION forming part of Letters Patent No. 722,260, dated March 10, 1903.

Application filed May 13, 1901. Serial No. 59,935. (No model.)

To all whom it may concern:

Be it known that I, WILLIAM A. SLOAN, of Cincinnati, in the county of Hamilton and State of Ohio, have invented a new and useful Improvement in Hair-Pins; and I do hereby declare that the following is a full, clear, and exact description thereof, reference being had to the accompanying drawing, and to the letters of reference marked thereon, making a part of this specification.

This invention consists in the construction of the hair-pin of one piece of spring-steel wire or other elastic material bent at the center *a*, forming a **U** shape, the ends of the **U** curving outward, forming arcs *b b'*. The wire is bent again, forming arcs at *c c'*, then merging into two straight tines *d d'*, touching at *e e'* near its ends, which are pointed and bent outward at the point of contact. The object in having the ends bent outward is to cause the hair-pin to automatically open when inserted in the hair.

The elastic material from which the pin is made serves to keep it in position when once inserted. The narrow **U**-shaped part serves to make the hair-pin practically invisible. As the wide part *c c'* displaces hair on being inserted, it will have a tendency to close over the hair-pin at *b b'* when inserted. This also helps to hold the pin in place.

What I claim as my invention, and desire to secure by Letters Patent, is—

1. A spring hair-pin formed of one piece of spring-wire or other elastic material in such a manner as to leave a **U**-shaped top *a* at the ends of the **U** being bent outward in an arc of a circle *b b'* merging into arc *c c'* then continuing into two straight tines *d d'* and touching near their ends which are pointed and bent outward at their point of contact *e e'*. 40

2. The herein-described hair-pin, the same comprising a pin with a plurality of members meeting at the top in a curve, said curve opening outward into a smaller curved portion or closed loop, substantially as set forth and described. 45

3. A hair-pin having a comparatively narrow and elongated loop at the head, and having the legs bent outward on each side from said loop, and then bent downwardly to complete the hair-pin, substantially as and for the purpose set forth and described. 50

In testimony whereof I have signed my name to this specification in the presence of two subscribing witnesses.

W. A. SLOAN.
